UNITED STATES PATENT OFFICE.

JOHN MERVIN, OF JOHNSTOWN, PENNSYLVANIA.

CHECK HANGER FOR MINE CARS.

Application filed July 19, 1923. Serial No. 652,625.

To all whom it may concern:

Be it known that I, JOHN MERVIN, a citizen of the United States, residing at Johnstown, in the county of Cambria and 5 State of Pennsylvania, have invented certain new and useful Improvements in Check Hangers for Mine Cars, of which the following is a specification.

This invention relates to devices for securing identification checks to mine cars.

It is common practice, where mine cars are used, for the miners to attach identification checks to the cars, when they are filled with ore, coal or other substances, for 15 the information of the check weighman. These cars, when new, are supplied with wire nails or hooks for the purpose of securing the checks to the cars, but these wire hooks soon break off, making it necessary 20 for the miners to secure the checks by means of wires wrapped or tied to some portion of the car, thereby necessitating a loss of time as well as making it inconvenient for a check weighman to remove the checks when 25 thus secured.

It is therefore the principal objects of this invention to overcome these disadvantages and objections by providing devices which may be secured to sides of mine cars 30 and which will effectively hold checks; and, to provide devices of the above mentioned character to which checks may easily be attached or secured to cars, and conveniently removed therefrom when desired.

35 Further objects and advantages will appear in the following detailed description, taken in connection with the accompanying drawing, forming a part of this specification, and in which drawing:

40 Figure 1 is an elevation of a mine car equipped with a check holder constructed according to my invention.

Figure 2 is an enlarged front view of the check holder, and,

45 Figure 3 is a longitudinal section thru the same, showing it attached to a fragment of a mine car.

In the drawings, wherein for the purposes of illustration is shown the preferred 50 embodiment of my invention and wherein similar reference characters designate corresponding parts throughout the views, the letter A indicates a mine car; B, an identification check; and C, a check holder comprising a bracket D; an arm E, and means F for operating said arm.

The mine car A may be of any approved type and size and has a side wall 5 to which the check holder C may be secured.

The identification check B may also be 60 of any approved shape and size and may have stamped or otherwise delineated thereon a number of other indicia serving to identify the party sending the car to the check-weighman. A perforation 6 may be 65 provided in the check B so as to secure it to the check holder C which will subsequently be described.

Referring now to the bracket D of the check holder C, it preferably is secured to 70 the side C of the car A by suitable fastening elements, such as rivets 7, said rivets passing through the bracket D adjacent the ends thereof. An intermediate portion 8 is provided between the rivets 7 and in 75 spaced relation to the car side 5. This intermediate portion 8 may be formed by having a portion 10 extending outwardly from a point adjacent the one end 9 and then formed as at 11 so as to extend for 80 a ways in plane parallel with the car side 5. The intermediate portion is then bent outwardly in arcuate formation as at 12, the arcuate portion 12 being provided with 85 a slot 13 which defines a pair of lips 14 and 15 respectively, the purpose of which will appear hereinafter. This arcuate portion 12 is then formed inwardly as at 16 toward the car side 5 until a portion 17 contacts with the side 5, said contacting members 90 being secured together by another rivet 7. A portion 18 then preferably extends outwardly from the side 5 and has the end thereof formed so as to provide an extension 19 which may be disposed in a plane 95 parallel to the car side 5, and defining a stationary jaw. This extension 19 may have a transverse perforation 20 therethru.

The arm E may be pivoted intermediate its ends between the lips 14 and 15 of the 100 bracket D by means of a pin 21 passing therethrough. The one end of the arm E may be provided with a hook or catch 22 defining a movable jaw and which is adapted to project into the perforation 20 of the 105 extension 19. The inner face 23 of the hook 22 may be inclined as is shown in the drawings to facilitate in the removal of a check. The opposite end of the arm E may be of such formation as to provide a relatively broad hand piece 24 for the purpose of moving the hook 22 out of engagement 110

with the extension 19 when it is desired to place a check therebetween. The arm E may also be provided with a perforation 25 intermediate the hand piece 24 and the 5 pivotal connection 21.

Referring now to the means F for operating the arm E, that is, for normally urging the hook 22 of the arm E toward the extension 9 or into clamping relation with 10 said extension 19 when a check B is interposed therebetween, it is herein shown as a coil spring 26 seated on the portion 11 of the bracket D. A screw or bolt 27 may be threaded into the seat 11, extending through 15 the coil spring 26 and perforation 25 in the arm E, thereby preventing the spring from displacement and acting as a guide for the arm E. It is obvious that other means could be employed for the above purpose and such as is illustrated is merely by 20 way of example.

When it is desired to use a device such as has been described in combination with a mine car, a miner or other person desiring to attach an identification check to the car takes the check in one hand and with the other hand pushes inwardly on the hand piece 24, thus moving the hook 22 away from the extension 19 of the bracket D. 25 The check is then placed so that the perforation 6 therein aligns with the perforation 20 of the extension 19, and the hand piece 24 is then released. The spring 26 will then force the arm E so that the check 30 B will be held by the hook 22 securely against the extension 19 and in spaced relation to the car side 5. When the car A reaches the check weighman he merely 35 has to grasp the check B and exert a downward pull and the check will slip over the inclined face 23 of the hook 22 and will 40 be detached from the device C. By using such a device a check may be attached to a mine car so as to always be in the line of 45 vision for inspection, not rendering it necessary for an inspector or check weighman to hunt all over the car before finding the check.

It is obvious that such a check holder A 50 may be used for purposes other than on mine cars, but it is primarily intended for use with such.

Changes in details may be made to the 55 form of the invention herein shown and described without departing from the spirit of the invention or the scope of the claims.

I claim:

1. A check hanger comprising a bracket including an intermediate portion and end 60 portions, one end of said bracket being bent to extend outwardly beneath the intermediate portion and having an exten-

sion forming a foot, said foot being provided with a perforation, an arm pivoted to said intermediate portion having a hook 65 at one end thereof, said hook adapted to project into said perforation in said foot for extending through a perforated article to be engaged by said hook, and into the perforation of the foot and means for yieldably holding said arm in a normal position 70 with the hook extending into the perforation of the foot.

2. A check hanger comprising a bracket including an intermediate portion and end 75 portions a longitudinal slot therein providing a pair of spaced lips, one end portion of said bracket being bent to provide a foot positioned beneath the intermediate portion and provided with a perforation, an 80 arm pivoted between said lips having a hook at one end thereof, said hook adapted to project into said perforation in said foot and means for yieldably holding said arm in a normal position with the hook extending 85 into the perforation.

3. A check hanger comprising a bracket including an outwardly bowed intermediate portion and end portions, said intermediate portion having a longitudinal slot 90 therein providing a pair of spaced lips, one end portion of said bracket being bent to provide a foot positioned beneath the intermediate portion, said foot being provided with a perforation, an arm pivoted 95 between said lips having a hook at one end thereof defining a movable jaw, said hook adapted to project into said perforation in said foot and provided with an inclined inner face, and means for holding said jaws 100 in a closed position, with the hook passing through a perforation in a check positioned between said jaws and into the perforation of said hook, said check being removable 105 therefrom by exerting a pull which will engage said inclined inner face and force said jaws apart.

4. As an article of manufacture, a hanger for perforated checks comprising a bracket including an intermediate portion, the one 110 end of said bracket providing a stationary jaw, an arm pivoted to said intermediate portion having a hook at one end thereof defining a movable jaw, said hook having an inclined inner face, and means 115 for holding said jaws in a closed position, said check adapted to be gripped between said jaws and have said hook extending thru the perforation therein, said check being removable therefrom by exerting a 120 pull which will engage said inclined inner face and force said jaws apart.

JOHN MERVIN.
